(74) Attorney, Agent, or Firm—Marshall, Gerstein & Borun LLP

(57) CLAIM

The ornamental design for a writing instrument, as shown and described.

DESCRIPTION

FIG. 1 is a perspective view showing our new design for a writing instrument;

FIG. 2 is a rear view of the writing instrument of FIG. 1;

FIG. 3 is a front view of the writing instrument of FIG. 1;

FIG. 4 is a right side view of the writing instrument of FIG. 1, the left side view being a mirror image thereof;

FIG. 5 is a top plan view of the writing instrument of FIG. 1;

FIG. 6 is a bottom plan view of the writing instrument of FIG. 1; and,

FIG. 7 is a perspective view of the writing instrument of FIG. 1 with cap removed.

The broken lines showing lines and portion of the writing instrument are included for the purpose of illustrating environment and form no part of the claimed design.

1 Claim, 2 Drawing Sheets
